UNITED STATES PATENT OFFICE.

EDWARD ANSELL, OF SCHREIBER, ONTARIO, CANADA, ASSIGNOR OF ONE-HALF TO
BENJAMIN GEORGE MAY, OF SCHREIBER, ONTARIO, CANADA.

VAPOR LAMP.

Application filed March 1, 1926. Serial No. 91,582.

The invention relates to improvements in vapor lamps as described in the present specification and shown in the accompanying drawings which form part of the same.

5 The invention appertains particularly to the well known "Coleman Lamp", Patent Number 1,303,462, vapor-burner, May 13th, 1919 granted to William C. Coleman. In this lamp the burner is provided with a vertical generator for the production of gas and the lamp lit by initially heating the generator, for which purpose a match or torch is usually employed, the mantles themselves maintaining the heat of the generator 10 when once lit.

In the use of this lamp it has been found that the generator frequently becomes clogged owing to carbonization which necessitates its removal from the burner for 15 cleaning purposes.

For this purpose it is imperative that a lock nut shall be loosened in order to permit of the withdrawal of the generator coil. In slackening this lock nut, however, it has 20 been found that the coil usually turns with the nut owing to the fact that there is nothing to retain it in place with the result that mantles suffer considerable damage; frequently being entirely destroyed. It is, 25 therefore, the object of the present invention to devise means for preventing the turning of the generator coil. A further object of the invention is to provide a platform for supporting the torch which heats the coil 30 in order to leave the hands of the party free to manipulate the lamp.

The invention consists substantially of a guard straddling the generator coil and carrying a platform located therebeneath for 35 the supporting of the torch.

Referring to the drawings, Figure 1 is 40 a side elevation of a burner in dot and dash lines showing the invention applied thereto in solid.

45 Figure 2 is a transverse sectional view taken on the line 2—2 of Figure 1 depicting the clip for attachment to the burner tubes from which the mantles are suspended.

50 Figure 3 is a similar figure to Figure 2 depicting a slightly modified form of clip. Figure 4 is a front view of the invention illustrating in dot and dash lines a fragmentary portion of the burner.

55 Figure 5 is a transverse sectional view taken on the line 5—5 of Figure 1, more par-

ticularly depicting the platform for the support of the torch.

Like numerals of reference indicate corresponding parts in each figure throughout the drawings.

In the drawings, the reference numeral 1 indicates a back plate which extends upwardly from the casting 2 of the burner to the bend 3 of the main tube 4 and terminating a slight distance above the said bend. 60 This back plate is preferably of an arcuate shape as shown at 5 Figure 5 in order to partially encircle the main tube 4. 6 is a platform located slightly beneath the coil 7 of the generator 8 and this platform comprises a substantially U-shaped member 65 having its bight 9 surrounding the tube 4 and affixed in any manner convenient to the inside of the back-plate 1. 10 is a pair of outwardly projecting wings constructed 70 integral with or secured to the said U-shaped member. These wings support the torch 11 which is placed thereon, at the time of lighting the lamp, in order to heat the coil 7, and removed when sufficient gas is 75 generated. The term "torch" is of course understood to designate any form of lighting instrument used for the purpose described—frequently a match. This torch is 80 more or less diagrammatically illustrated 85 in the drawings.

12 is a square headed bolt passing transversely through the arms of the U-shaped member in close proximity to the pipe 4 in order to clamp said arms about the main 90 tube.

Rising from each of the arms of the platform are guards 13 and 14 which straddle the coil 7 at its outer end and thus prevent it from turning in either direction. These 95 guards may be constructed integral with the platform as shown in the drawings or secured thereto as found desirable.

15 is a substantial U-shaped brace, the bight 16 of which surrounds the bend 3 100 of the main tube and is affixed to the upper portion 17 of the back plate 1 in any convenient manner. The extremity of the arms of the brace are attached to the corresponding guards 13 and 14. 18 is a bolt passing 105 through the brace and held by a nut in order to clamp it about the bend 3 of the tube. 19 is a clip attached to the top end of the back-plate 1 and extending transversely thereof; the opposing ends of this 110

clip are provided with substantial C-shaped clamps 20 which extend at right angles to the cross member 21 in order that the attachment as a whole may be removed from the burner without necessitating the removal of the burner tubes 22 which these clips embrace.

23 are bolts and nuts for drawing together the ends of the clamps 20.

10 In the modified form of clip shown in Figure 3, the difference consists in placing these clips so that they extend outwardly from the cross-member 21 which necessitates the dismantling of the burner tubes 22 in order to remove or attach the clip from or to the burner. It will be apparent that in turning the locknut 24 of the generator either guard 13 or 14 will be strained in accordance with the direction of movement and in order that the guards shall equally bear this strain it is proposed that a catch be provided as at 25, which may take the form of a member pivoted as at 26 to the platform and having a handle 27 at one end, the other end being slotted as at 28 to receive the guard. In the normal use of the lamp this catch occupies the position shown in dotted outline at 29 in Figure 5, and it will only be used in the removal or replacement of the generator.

Whereas in the preferred form of the invention this device has been shown as an attachment to the burner of the lamp, it is, of course, distinctly understood that the 35 whole contrivance may be constructed as an integral part of the lamp itself.

When used as an attachment it may be simply detached from the lamp by removing the bolts and nuts by which it is secured thereto. It may also be remarked that in the event of a small hole developing at the bottom of the mantles the platform will act as a shield and prevent the flame from shooting down and burning the valve 30.

45 What I claim is:—

1. In a vapor lamp of the class described, the combination with a removable generator, of guards borne by the burner and situated on each side of the generator coil to preclude its lateral movement.

50 2. In a vapor lamp of the class described, the combination with a removable generator, of guards borne by the burner and situated on each side of the generator coil to preclude its lateral movement, and a catch for securing said guards to each other.

55 3. In a vapor lamp of the class described, the combination with a removable generator, of guards borne by the burner and situated

on each side of the generator coil to preclude its lateral movement, the said guards terminating in a platform at their lower ends for supporting a torch.

4. In a vapor lamp of the class described, the combination with a removable generator, of a platform located below the generator-coil, and guards rising from said platform one on each side of the coil to preclude its lateral movement.

5. In a vapor lamp of the class described, the combination with a removable generator, of a platform located below the generator coil, guards rising from said platform one on each side of the coil to preclude its lateral movement, a catch for securing said guards one to the other, and means for bracing the upper ends of the guards.

6. In a vapor lamp of the class described, the combination with the main tube and removable generator, of a back plate extending lengthwise of the main tube, a U-shaped member having its bight affixed to said back plate, wings extending from the arms of said U-shaped member, guards rising from the ends of said arms, and means securing the back plate to said main tube.

7. In a vapor lamp of the class described, the combination with the main tube and removable generator, of a back plate extending lengthwise of the main tube, said back plate being of an arcuate cross section, a U-shaped member having its bight passing around said main tube and fixedly secured to said back plate, wings extending from the arms of said U-shaped member, guards rising from the ends of said arms, one on each side of the generator coil, a U-shaped brace having its bight passing around said main tube and fixedly secured to said back plate, the arms of said brace being attached to the upper ends of said guards, and bolts and nuts detachably clamping the aforesaid U-shaped member and brace to the main tube.

8. In a vapor lamp of the class described, the combination with the main tube and removable generator, of a back plate extending lengthwise of the main tube, a U-shaped member having its bight affixed to said back plate, wings extending from the arms of said U-shaped member, guards rising from the ends of said arms, means securing the back plate to said main tube, and a catch pivoted to one of said wings adjacent to a guard for swinging over to and engaging the other guard.

Signed at Schreiber, Ontario, Canada, the ninth (9th) day of February, 1926.

EDWARD ANSELL.
